MEANS AND METHOD OF DUPLICATING

Gertrude L. Nachman, Chicago, Ill.

Application April 30, 1937, Serial No. 139,971

3 Claims. (Cl. 101—126)

The present invention relates to a method and means for making duplicate records by the use of a stencil sheet.

It is particularly applicable to the making of records such as are used in insurance work where certain of the cards or sheets which are made for record purposes are relatively large and contain a complete record while others are smaller in size and contain only partial records.

10 Stencil sheets have been used for many years for the making of a large number of copies of a master record. It is also possible to make partial records from stencils cut for a complete master record by using block-out sheets covering the 15 copy sheet except for that portion which is to be transferred to the copy sheet or card. In many instances, however, where these records are being made, the number of cards of any individual size is quite small while there may be several different 20 sizes of cards for each individual record. The stencil sheet is, therefore, used only for making a comparatively small number of copies and then is thrown away. This makes it possible to use a cheap or inferior stencil that would not be 25 capable of running a large number of copies. In order, however, to make the requisite copies on cards or sheets of different sizes, the necessity for supplying block-out sheets at each change in the size of card receiving the record or partial record 30 makes the process of duplicating the original record cut in the stencil a rather slow process thereby embodying a substantial labor cost.

It is the purpose of the present invention to provide a method and means of duplication from an original record cut on a stencil which will, to a substantial degree, eliminate this labor cost and at the same time effect a saving over the use of block-out sheets as a matter of material cost.

The features and advantages of the invention 40 will appear more readily as the description proceeds, reference being had to the accompanying drawings wherein a preferred embodiment of the invention is illustrated. It is to be understood, however, that the drawings and description are illustrative only and are not to be taken as limiting the invention except in so far as it is limited by the claims.

In the drawings—

Fig. 1 is a view in side elevation, certain parts 50 being shown in section, of a machine utilized in carrying out the present invention;

Fig. 2 is a plan section taken on the line 2—2 of Fig. 1;

Fig. 3 is an enlarged fragmentary view taken 55 substantially on the line 3—3 of Fig. 2, certain

parts being broken away to show the interior construction;

Fig. 4 is a view like Fig. 3 illustrating a changed position of the parts;

Fig. 5 is a fragmentary sectional view taken 5 on the line 5—5 of Fig. 4 with certain of the parts broken away to illustrate the interior construction;

Fig. 6 is a fragmentary view taken on the line 10 6—6 of Fig. 4; and

Figs. 7, 8, and 9 are diagrammatic views illustrating the manner in which the steps of the improved method of duplicating from a stencil sheet is carried out.

Referring now to the drawings, the machine 15 shown in Fig. 1 is what is commonly termed a flat bed type of stencil machine. In this figure, 10 designates a frame which carries an inking mechanism comprising an inking roller 11 and a series of rollers for supplying ink to the 20 roller 11, these rollers being a roller 12, a roller 13, a roller 14, and an additional roller not shown for supplying ink to the roller 11 from an ink reservoir 15. The roller 11 and the associated rollers are part of an inking carriage having a 25 handle 16 by means of which the carriage may be drawn forward over a bed plate 17. The inking carriage has guide racks 18 and 19 at the opposite sides of the frame. Suitable gear wheels 30 20 cooperate with the racks 18 and 19 to actuate 35 the rollers of the inking carriage as will be readily understood.

The details of the inking mechanism hereinbefore described are well known to the art and, therefore, will not be described further.

The frame 10 includes a base 21 for the bed plate 17, said base having suitable guide rails 22 upon which the bed plate 17 is slidable lengthwise. An adjusting rod 23 is secured to a bracket 24 on the bed plate 17, by a rotatable and non- 40 slidable connection consisting of a sleeve 25 carried by the bracket 24, a reduced section 26 of the rod 23, and a nut 27 securing the sleeve 25 on the reduced section 26 on the rod 23. The rod 23 is screw threaded in a boss 23' provided on the 45 base 21. The rod 23 has a knurled handle 28 by means of which it may be rotated to adjust the bed plate 17.

A stencil sheet holding frame 29 is carried upon a pair of standards 30 and 31 mounted on 50 the base 21. The stencil frame 29 is supported by a shaft 32 journaled in the standards 30 and 31. This stencil frame 29 comprises means for gripping and holding a stencil sheet therein, and it is adapted to be moved down from the posi- 55

tion shown in Fig. 1 over the bed plate 17 in a well known manner so that the roller 11 may travel over a stencil sheet held by the frame 29 and apply ink to a copy sheet under the stencil sheet 5 through the openings cut in the stencil sheet as will be readily understood. The frame 29 with the shaft 32 is adjustable transversely of the bed 17 in the base 21 by means of a cam 33 which rides between a pair of guides 34 and 35 secured on the shaft 32. The cam 33 is fixed on a shaft 36 which is journalled in a bracket 37 mounted on the base 21. A ratchet wheel 38 on the end of the shaft 36 cooperates with a spring pressed latch 39 to hold the cam 33 in any adjusted position.

15 The cam 33 is adapted to be actuated by a rod 40 which is secured thereto and passes through a bearing 41 adjacent the front end of the bed plate 17, the bearing 41 being carried by the bed plate 17. The rod 40 is provided with a knurled handle 42 by means of which it may be rotated. The adjustment of the bed plate 17 longitudinally on its guide rails 22, and the adjustment of the stencil carrying frame 29 transversely in the standards 30 and 31, are for the purpose of properly registering the stencil sheet with a copy sheet held on the bed plate 17. The stencil frame 29 is of a well known construction and, therefore, the details of this frame by which it grips the stencil sheet have not been shown or described.

20 Referring now to the bed plate 17, this bed plate comprises a rectangular frame 44 having a peripheral flange 45 at the top thereof. The flange 45 is integral with a cover plate 46 which is sufficiently rigid to form a solid backing for the sheets placed thereon when the inking roller 11 passes over the sheets. At the opposite sides of the frame 44 and across the end adjacent to the stencil sheet frame 29, I provide a U-shaped gripping frame 47. This frame is substantially L-shaped in cross section throughout most of its length so that a horizontal portion 48 thereof overlies the plate 46, and a vertical portion 49 thereof extends down past the flange 45.

25 At the opposite ends of the frame 47, the vertical portion 49 is turned under as indicated at 50 (see Figs. 3 and 4) so as to extend under the flange 45. Between the portions 50 and the flange 45, coil springs 51 are inserted under compression so that they tend to force the horizontal portion of the flange 48 of the member 47 down upon the plate 46. Across the back of the frame 47, a portion 52 thereof at the bottom of the vertical flange 49 is turned inwardly beneath the flange 45, and springs 53 are inserted so that they will urge the back end of the frame 47 down toward the plate 46.

30 Means are provided whereby the frame 47 may be lifted up so that a sheet 54 of absorbent material, such as blotter paper, may be inserted beneath the horizontal flange 48 and readily removed therefrom. This means comprises a pair of levers 55, one at each side of the frame 44, the two levers being keyed to a shaft 56 which is journalled in the frame 44. The levers 55 project beneath the back portion of the frame 47 and may be engaged therewith as indicated at 57 in Fig. 4 so as to lift up the back end of the frame 47 against the tension of the springs 53. Two bell crank levers 58 are pivoted on studs 59 in the opposite sides of the frame 44, one end 60 of each bell crank lever extending beneath the lever 55, and the other end 61 of each bell 55 crank lever 58 extending beneath the flange 50

of the frame 47, as illustrated clearly in Figs. 2, 3, and 4.

It will be evident that, if the ends 57 of the levers 55 are pressed upwardly so as to lift the back end of the frame 47, the opposite ends of the levers 55 will move downwardly against the ends 60 of the bell crank lever 58 so as to force the ends 61 of the bell crank levers up against the flanges 50 and force the side portions of the frame 47 upwardly also, thus making it possible to insert or remove the sheets 54 with no difficulty. The sheets 54, however, act as backing sheets for copy sheets or cards 62 upon which the stencil is laid and to which the ink is to be applied to make a copy of the record cut in the stencil sheet.

20 In order to grip the sheets or cards 62, suitable gripping means consisting of a plurality of gripping fingers 63 are carried by the ends 57 of the levers 55. These fingers 63 are formed at the upper end of strips 64 by bending the strips over as indicated best in Figs. 3 and 4. The strips 64 are set into a bar 65 and fastened thereto by screws 66, as shown in Fig. 6. The bar 65 has reduced cylindrical end portions 67 which are journalled in the ends 57 of the levers 55 so that the bar 65 moves up and down in response to movements of the levers 55. Springs 68 are seated in the levers 55 and press against the under surface of the flange 45 so as to normally urge the levers 55 downwardly at the ends which are secured to the bar 65 and thus normally urge the fingers 63 into clamping position upon card 62 inserted beneath these fingers.

25 For the purpose of guiding the frame 47, the forward ends thereof are provided with vertically elongated slots 69, and screw bolts 70 are threaded into the flange 45.

30 The lever 55 is lifted by a cam 71 fixed on a shaft 72. The shaft 72 is journalled in a bearing block 73 which is fixed to the frame 44 by screws 74. At its outer end, the shaft 72 has fixed thereto an arm 75 and the arm 75 at its free end carries a pivot block 76 to receive an operating rod 77. The operating rod 77 extends to the front end of the frame 44 and is secured in a guide block 78 so that the rod 77 can slide freely in the block 78. A handle 79 is fixed on the rod 77.

35 It will be noted that the cam 71 has a substantially flat face at 80. The three positions taken by the cam 71 are as follows: When both the frame 47 and the clamping fingers 63 are in their lowermost position, the cam 71 is in the position shown in Fig. 1. That is, the rod 77 has been pulled out to such an extent that the cam 71 is completely out of the way of the levers 55 when the ends 57 thereof are in their lower limiting position. Now, by pushing in on the rod 77, the operator can move the cam 71 into the position shown in Fig. 3. In this position, the flat face 80 rests solidly against the lower surface of the left hand lever 55, and the shaft 56 has been rotated so as to turn both levers 55 in a clockwise direction, when viewed as in Fig. 1, sufficiently to bring the ends 57 thereof substantially up against the bottom edge of the frame 47 and to lift the fingers 63 off of the card 62 thus permitting the ready replacement of the card 62 without lifting the frame 47. By pushing further in on the rod 77, the cam 71 can be made to take the position shown in Fig. 4 where it causes additional rotation of the shaft 56 so that the levers 55 and the levers 58 also lift the frame 47 to bring the horizontal flange 48 there- 75

5 of above the absorbent sheet 54 whereby this sheet may be readily removed and replaced when necessary. The flat surface 80 on the cam 71 makes it easy for the operator to determine when the fingers 63 have been raised so that he does not raise the frame 47 except when necessary.

10 Now in the method of forming copies on several different sizes of cards and sheets as hereinbefore outlined, in the objects of the invention, this machine is particularly adapted to carry out the steps of that method because of the ease with which the cards 62 and the absorbent backing sheet 54 can be placed in the machine and removed. Referring now to Figs. 7, 8, and 9, the 15 method of duplicating will be more fully described. When it is desired to reproduce upon record cards one or more copies of original information, a stencil of the usual type is cut in the usual manner with all of the information 20 that it is necessary to have appear upon the most complete record card or sheet that is to be formed. Other cards or sheets which contain incomplete records are so formed as to be smaller, either in length or width or both, than the complete card. The record material to be placed upon the cards is also so arranged that the part 25 of the record to be transferred to a smaller card shall be upon a restricted area of the stencil. For purposes of convenience, the upper left hand 30 corner of the stencil sheet, or rather of that portion of the stencil sheet which is to be utilized in making the copies, is taken as a reference point. The material which is to be placed upon the smallest card of any series is arranged closest to this upper left hand corner in short lines running 35 across the sheet, the lines being spaced in the usual manner. Other data to be placed upon larger sheets or cards may be extended to the right of and below the data which is to be placed upon the smallest of the cards to be made.

40 Arranging the data in this fashion, develops a complete arrangement of the data on the stencil sheet in such a fashion that registering the upper left hand corner of all of the cards as they are placed under the stencil will result in the proper information being supplied to the cards. Of course, it is possible to take another reference point such as the upper right hand corner and to arrange the data from this point so that the 45 arrangement of the data offers no limitation in so far as the method to be hereinafter outlined is concerned.

50 In carrying out the method, a stencil sheet is cut with the entire or complete record thereon, and, where a complete copy is desired as is usual, the first step is to place a card 62 large enough to receive the complete copy upon an absorbent sheet 54 and apply the stencil thereto after which ink is applied to the stencil in the usual manner, 55 as for example by the roller 11 in the machine just described. By doing this, as many copies of the complete record can be made as are needed. The next step is merely to substitute the next smaller card than the card big enough to receive 60 the complete copy, such for example as the card 62A shown in Fig. 8. The stencil is applied over the card 62A and the absorbent sheet 54 and inked as before. The proper data is printed upon the smaller card and the ink through the remaining 65 portion of the stencil goes upon the absorbent sheet 54. When the requisite number of copies on this size of card has been made, the card next smaller in size is substituted. This for example may be the card 62B shown in Fig. 9 70 of the drawings. The stencil is again placed over

the card and the inking done as before. In this instance, absorbent sheet 54 receives a greater amount of ink as it receives not only ink over the portion of the stencil formerly extending beyond the card 62A, but it also now receives ink over a 5 part of the surface that was covered by the card 62A.

10 By this method of making copies from the stencil, a single stencil sheet can be used without block-out sheets and without marring the 15 copies to make many different sizes of record copies. As many as fifteen different sizes have been made without difficulty. Only one stencil and one absorbent sheet is necessary for any series. The saving in labor and in block-out 20 sheets is far more than the cost of the absorbent sheet.

25 The absorbent sheet and the stencil sheet itself are thrown away after the completion of a series, and, since the number of record or filing 30 copies made by this method is usually comparatively small, it is not necessary to use a very expensive stencil sheet or a very expensive absorbent sheet. The machine shown herein is an efficient and effective means for carrying out the 35 method since the absorbent sheet is readily replaced by a simple operation which releases it completely from the bed of the machine. The strips 64 provide stops for the absorbent sheet so that, in placing it in the machine, it is quickly 40 positioned. The horizontal flange 48 of the frame 45 47 provides a margin for locating the cards or sheets to receive the copy. The stencil frame and bed plate adjustments are sufficient for registering the stencil with the bed plate under all 45 ordinary conditions.

50 I have referred in the description to the copy sheets as copy sheets or cards indiscriminately, and it is to be understood that the terms are used interchangeably in their broader sense to include 40 a sheet capable of receiving an imprint from the ink transferred through the stencil. It is also to be understood that, where the absorbent sheet is referred to herein, it is not to be considered a limitation since the sheet may be in 45 the form of a single rectangular sheet or an elongated sheet or web, successive portions of which are fed to supporting position for the card.

55 From the above description, it is believed that the method and means hereinbefore described 50 will be readily understood by those skilled in this art and the advantages thereof will be readily apparent.

Having thus described my invention, what I 55 claim as new and desire to secure by Letters Patent is:

1. A method of producing complete and partial copies of records from a single stencil sheet which comprises cutting the stencil sheet for the complete copy, placing a card to receive the 60 complete copy upon a bed plate having a separable supporting sheet for said card capable of absorbing ink, placing the stencil sheet upon the card and sheet and applying ink through the stencil to ink the complete copy upon the card, 65 lifting the stencil sheet and replacing the previous card with successively smaller cards while retaining the supporting sheet, placing the stencil over each card in turn and inking the entire stencil whereby successively smaller areas of 70 card receive ink through the stencil and successively larger areas of the supporting sheet receive ink through the stencil.

2. A method of producing, from a single stencil having a master record thereon, a plurality 75

of records including complete and partial copies of the master record which comprises placing the card large enough to receive a complete copy of the master record upon a sheet of material capable of absorbing ink, applying the cut stencil to said card and applying ink through the stencil whereby to reproduce the master record upon said card, successively lifting the stencil sheet and replacing the card on the absorbent sheet with a smaller card, placing the stencil over each card in turn and inking the entire stencil each time whereby each time a smaller card is inserted a larger surface of the absorbent sheet receives ink through the stencil.

3. Means for producing from a single stencil sheet having a master record thereon, a plurality of records including complete and partial copies of the master record, said means comprising a bed plate, an absorbent sheet covering at least a portion of said bed plate, manually controlled clamping means for clamping said absorbent sheet to the bed plate, and clamping means for clamping a card upon said absorbent sheet, and a manually operable member for releasing the card clamping means and the absorbent sheet clamping means.

GERTRUDE L. NACHMAN.
